UNITED STATES PATENT OFFICE.

EVA B. BATTERTON, OF SPRINGFIELD, ILLINOIS.

DESIGN FOR A PRINTED FABRIC.

59,808.

Specification for Design.

Patented Nov. 29, 1921.

Application filed May 24, 1921. Serial No. 472,262. Term of patent 7 years.

To all whom it may concern:

Be it known that I, EVA B. BATTERTON, a citizen of the United States, residing at 1114 West Monroe street, Springfield, in the county of Sangamon and State of Illinois, have invented a new, original, and ornamental Design for a Printed Fabric, of which the following is a specification, reference being had to the drawing, forming part thereof.

The drawing is a plan view of a piece of ribbon, embodying my new design.

This design for printed fabric is adapted to be printed on bunting, ribbons and the like for use on patriotic occasions.

I claim:

The ornamental design for a printed fabric as shown.

EVA B. BATTERTON.
